UNITED STATES PATENT OFFICE

HERMAN KLEIN, OF CHICAGO, ILLINOIS

INCINERATOR

Application filed October 4, 1926. Serial No. 139,326.

My invention relates to incinerators and to those associated with the fire pot A, I provide has to do more particularly with incinerators for household use adaptable for burning garbage and other combustible refuse. My invention is also more particularly directed to the gas burning type of incinerator, an object being to provide an improved and simplified apparatus of the above character having certain features of construction and 10 operation also leading to improved results.

For a better understanding of my invention reference is to be had to the accompanying drawings, in which—

Fig. 1 is a side elevation of my improved 15 incinerator shown partly in section;

Fig. 2 is a vertical cross section along the line 2—2 of Fig. 1 through the fire pot, grate and dryer;

Fig. 3 is a top plan view of Fig. 2;

Fig. 4 is a top plan view of the grate with the top cover plate removed;

Fig. 5 is a cross sectional view along the line 5—5 of Fig. 4; and

Fig. 6 is a sectional view through the 20 cover plate adapted to fit over the top of the burner or grate of Fig. 4.

Referring now more in detail to the construction employed, I provide a suitable base 10 preferably circular and having the legs 11 secured thereto. The base 10 has an outer flange so that an outer casing or sheet metal 25 enclosure 12 may set therein. A door 13 is provided through which access is had to the ash pit.

Now as to the drying and burning apparatus of the incinerator, I provide a suitable fire pot A preferably frusto-conical at its upper portion 14 and having a plurality of lugs 15 by which the pot and grate are supported, 30 these lugs resting upon tubes or pipes 16 which extend to the base and having tie rods 17 extending therethrough and passing downwardly through the base so as to clamp the parts in position. The outer casing 12 is also 35 attached to the lugs 15 by angle pieces 18 having the lower leg secured to the lug 15 by the head of the tie rod 17 and having a bolt 19 passing through the casing 12 so as 40 to be rigidly and securely held in place.

Now as to the drying and burning appara-

60 preferably a gas burning grate B of an inverted V-shape arrangement and tiltably supported upon its shaft extensions 20—21 which fit up into slots 22 in the lower wall of the fire pot. The grate is held up in these slots by caps 23 which are secured to the outer face of the fire pot by screws so that they may be readily removed to permit dropping down and removal of the grate.

65 The grate B is preferably composed of a lower section shown more in detail in Figs. 4 and 5 in the form of a hollowed casting to which the gas is fed through the hollow shaft 21. In order to overcome certain defects in prior incinerators I have provided certain improved features of construction in my present grate making it in the form of an inverted V-shape. By this arrangement the 70 refuse when dumped into the fire pot does not settle upon a horizontal surface but rests upon an inclined surface so that it will more readily slide off its support when the grate is tilted and also requires a less angular tilting movement to dump the grate. This will be 75 apparent from an inspection of Fig. 2, for as here shown the downwardly sloping upper surface of the grate is tilted or dropped downwardly into a vertical position with less angular movement than if the grate surface 80 were horizontal or straight across. Thus unburned refuse such as tin cans and other substances may be readily dropped through with a movement that otherwise would not clear 85 the grate. This is important when we consider that these incinerators are frequently operated by people who are careless in their handling of the apparatus.

Considering the construction of the grate 90 more in detail, as previously stated the lower portion is in the form of a hollow cast iron member having passages 24—25—26 through which the gas flows from the central passage 27 to the outer passage 28, thereby feeding the gas to the burner openings 29 around the outer edge of the burner and also to the small burner openings 30—31 which direct a flame into the openings 32—33 passing through the grate. A cap or cover plate C 95 forms a part of the grate and comprises a 100

ribbed casting having an inner V-shaped surface to fit down over the top of the lower portion B as indicated in Fig. 2. This cover plate C has openings 34—35 to conform to the rectangular openings in the lower portion of the grate and has a refuse supporting surface in the form of a plurality of ribs 36 suitably spaced to properly support the refuse to keep it from clogging the grate or sticking between the ribs. It will be noted that the upper portion or apex of the grate is rounded at 37, thereby giving greater clearance for the dumping of the refuse when the grate is tilted. That is, this gives greater clearance than if the grate were run up to a point. At the apex of the grate I provide a row of burner openings 38 adapted to send a flame up into a dryer positioned above, and which will be hereinafter more particularly referred to. This grate cover also has a plurality of burner openings 39—40—41—42, indicated in Fig. 3, so positioned that when the gas is turned on and a light applied to any point of the burner, the flame will automatically creep along the burner openings and light the burner all over.

Referring now to the gas feeding means for the grate, as previously stated the gas is fed through the hollow shaft 21 and is fed thereto from the gas supply pipe 44 controlled by the valve 45. The enlarged head of the shaft 21 is adapted to pass through a clearance hole 46 in the casing 12, which opening is covered by a split cover plate 47 adapted to be removed when the grate is to be taken out. That is, the split cover plate 47 is taken off before the enlarged head of the shaft 21 can be drawn through the opening 46 of the casing.

Now as to the tilting or dumping apparatus for the grate, this is in the form of a handle 48 pivotally attached to a shaft 49 removably pinned at 50 to the grate shaft 20. This tilting or dumping apparatus is arranged so as to be properly returned to normal and thereby to centralize the grate in the fire pot, this being done for several reasons, one being that the grate is then maintained in proper closed relationship to the fire pot and also the burner holes at the apex are maintained beneath the drying wall.

The handle 48 is spring retracted by a spring 51 extending from the handle to a lug 52 which latter lug also acts to limit the tilting movement of the grate. To this end I provide oppositely disposed lugs 53, shown in dotted lines in Fig. 1, extending from the plate 54 on opposite sides of the shaft 49. To lock the grate in its centralized or normal position I provide a slotted lug 55 at its upper portion, the slot of which receives the lug 56 carried by the handle 48. In the operation of the dumping apparatus the handle 48 is grasped and pulled outwardly against the tension of spring 51 until the lug 56 is clear of

lug 55. The handle may then be moved to the right and left, its movement being limited by engagement between the coacting lugs 52 and 53. These lugs are so disposed that a sufficient tilting movement of the grate is secured to give the upper or supporting surfaces of the ribs 36 a vertical position and thereby the greatest opening in the fire pot to drop the burned refuse. After shaking or dumping the grate the handle 48 is returned to its central position and the lug 56 permitted to re-engage the slot in lug 55, thereby properly positioning the grate in the fire pot.

Considering now the drying apparatus previously referred to, this is in the form of a chambered separating wall D vertically disposed centrally above the grate and preferably set down in the fire pot so that the garbage and refuse dumped therein will be quickly dried before dropping down to be consumed by the gas flames at the grate.

This dryer D is preferably in the form of a pair of similar but oppositely disposed sections 60—61 suitably bolted together so as to form a unitary structure. This dryer is preferably of an inverted V-shape with the apex 62 at the top and the inclined edge walls 63—64 sloping down toward the fire pot. This dryer is also preferably provided with an upper pointed edge so that the garbage and refuse striking the same will drop down along each side and separate to come into association with the heated opposite walls of the dryer and also exposed to the heat emanating from the opening 65 in the side walls and which heat comes from the gas flames directed upwardly from the center holes at the apex of the grate. I also provide openings 66 along the upper edge of the dryer, these openings slanting downwardly as indicated in Fig. 1 but permitting the heat from the interior of the chamber to flow outwardly to assist in drying the refuse dumped in the incinerator.

It will be noted that the flat side walls 60—61 of the dryer slope inwardly toward the bottom, thereby providing walls which gradually recede from the vertical. It will thus be seen that the refuse as it drops down over this wall falls away from it rather than down along in contact with it. By this construction packing is also prevented and thereby the heat from the dryer acts more rapidly upon the refuse. This is important, as it is most desirable that wet garbage be dried as rapidly as possible before reaching the actual flame which does the consuming.

This dryer D is arranged so that it may be readily placed in the fire pot and also removed therefrom, and to this end it is provided with a pair of bolts 67 which drop down into slots 68 formed in lugs 69 extending inwardly from the wall of the fire pot A.

Thus with the dryer constructed and posi-

tioned as illustrated and described, the heat from the flames along the apex of the grate readily flows directly upwardly into the chamber of the dryer, heating the same and 5 also flowing on and out through the openings in the wall thereof.

Above the dryer D is a receiving chamber E formed by a cylindrical inner wall 70 of sheet metal which sets down over the edge 10 of the fire pot resting upon the lugs 15 and then engaging the brackets 71 at the top of the casing. These brackets 71 are also bolted inside the outer casing 12 and to the top casting 72 which is provided with a suitable 15 opening and closure 73 so that the incinerator may be readily fed from above. I also provide a suitable opening at 74 to which a pipe may be attached for carrying away the fumes from the burning refuse.

20 Referring again to the receiving chamber E, it will be noted that this is in the form of a frusto-conical inner wall 70 smaller at its upper end and gradually enlarging as it approaches the fire pot. Thus the chamber being 25 larger at the bottom than at the top and with an outwardly extending wall, the refuse as it is dropped into the chamber has more room at the bottom than at the top and does not so readily pack and is also more accessible 30 by the heated air flowing into this chamber through the openings 75 in the wall thereof.

From the foregoing it will be apparent that in my improved incinerator by the use 35 of the single gas burning grate of the inverted V shape and with its double throw, the grate may be tilted for dumping by a small angular movement but at the same time providing a full dumping opening. At 40 the same time the side of the grate which is being raised is so shaped and positioned that it will still maintain that side of the fire pot grate opening sufficiently closed to prevent the refuse entering that side to interfere 45 with the restoration of the grate to normal. In other words, although one side of the grate is lowered to dump the grate, the other side or other half is maintained closed as that half of the grate comes up, so that 50 the refuse will not drop down between the grate and fire pot and prevent its restoration to normal as would occur in the ordinary flat grate.

Furthermore, in the improved gas burning 55 grate construction the gas burning openings are protected by the longitudinal but slanting ribs so that the garbage will not contact with and close up these flame openings. 60 Furthermore, by the improved gas burning grate a single integral structure is provided which acts as a grate for supporting the refuse being burned and also acts for conducting the gas to the flame openings, thereby 65 simplifying the structure over prior inciner-

ators where separate burners and grates are provided.

What I claim as new and desire to secure by United States Letters Patent is:—

1. A gas burning grate comprising an inverted V-shaped hollow grate member having suitable gas emitting openings therein along the bottom edge thereof, means for pivotally supporting the grate on its center with the opposite legs sloping downwardly from the apex so as to permit tilting either side downwardly to dump the grate, and a plurality of ribs formed upon the upper face of each leg extending from the apex to the peripheral edge with upper refuse supporting edges sloping downwardly and spaced to keep the refuse clear of the burner openings. 70 75

2. A gas-burning grate of rectangular plan, comprising a central apex-portion and downwardly and outwardly extending wing- 80 portions, said grate having a central conduit and peripheral conduits communicating with the central conduit and having burner- 85 ori-fices opening from said peripheral conduits at the base of said wing portions, the apex portion of said grate having rigid trunnions projecting from the apex-portion, one of which trunnions serves as a mixer-tube and communicates with said central conduit, said wings being equipped on their upper surfaces with ribs which slope downwardly and outwardly from the apex-portion of the 90 95 grate and increase in depth from the apex to the outer edges of the wings. 100

In witness whereof, I hereunto subscribe my name this 18th day of September, 1926.

HERMAN KLEIN.
